UNITED STATES PATENT OFFICE

150,745

DESIGN FOR A LUMINAIRE

Frederic C. Winkler and David T. Beggs, Cleveland, Ohio, assignors to Westinghouse Electric Corporation, a corporation of Pennsylvania

Application February 5, 1947, Serial No. 136,704

Term of patent 14 years

(Cl. D48—4)

To all whom it may concern:

Be it known that we, Frederic C. Winkler and David T. Beggs, citizens of the United States, residing at Cleveland, in the county of Cuyahoga and State of Ohio, have invented a new, original, and ornamental Design for a Luminaire, of which the following is a specification, reference being had to the accompanying drawing, forming a part thereof, in which the single figure is a perspective view of the luminaire embodying our new design.

We claim:

The ornamental design for a luminaire, as shown.

FREDERIC C. WINKLER.
DAVID T. BEGGS.
